Primary Examiner — John R Yeh*(74) Attorney, Agent, or Firm* — Oblon, McClelland, Maier & Neustadt, L.L.P.(57) **CLAIM**

The ornamental design for a cleaning sheet for skin, as shown and described.

DESCRIPTION

FIG. 1 is a front, right side, bottom perspective view for a cleaning sheet for skin;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a cross-sectional view taken from the line 8-8 of FIG. 2.

The broken lines illustrate portions of the cleaning sheet for skin that form no part of the claimed design.

1 Claim, 7 Drawing Sheets---
